UNITED STATES PATENT OFFICE

92,656

DESIGN FOR A TOILET COMPACT OR SIMILAR ARTICLE

Arthur L. Hyde, Haddonfield, N. J.

Application April 14, 1934, Serial No. 51,405

Term of patent 3½ years

To all whom it may concern:

Be it known that I, ARTHUR L. HYDE, a citizen of the United States of America and a resident of Haddonfield, Camden County, New Jersey, have invented a new, original, and ornamental Design for a Toilet Compact or Similar Article, of which the following is a specification, reference being had to the accompanying drawing, forming part thereof.

Fig. 1^a is a similar perspective view of the toilet compact, looking in a direction different from that illustrated in Fig. 1.

Fig. 2 is a plan view of the same.

Fig. 3 is an edge view looking in the direction of the arrow a, Fig. 2, and

Fig. 4 is an edge view looking in the direction of the arrow b, Fig. 2.

I claim:

The ornamental design for a toilet compact or similar article as shown.

In witness whereof I have signed this specification:

ARTHUR L. HYDE.
